REMOVAL OF PRIMARY ALKYL HALIDE
FROM HYDROCARBONS IN GASOLINE
BOILING RANGE

Joseph T. Horecza and Harry G. Boynton, Baytown, Tex., assignors, by mesne assignments, to Standard Oil Development Company, Elizabeth, N.J., a corporation of Delaware

Application May 19, 1951, Serial No. 227,266

3 Claims. (Cl. 260—676)

1

This application is directed to a method for removing primary alkyl chloride from a hydrocarbon fraction.

It is sometimes desirable or necessary to remove alkyl chloride or chlorides from a hydrocarbon fraction containing the same. Examples of hydrocarbon fractions contaminated by alkyl chloride or chlorides are the fractions obtained when isoparaffin is alkylated with a low boiling olefin and an active chloride is used as the catalyst. These fractions boil in the gasoline boiling range and are commonly used for gasolines and when so used the alkyl chloride contaminant is considered quite detrimental. It is desirable or necessary to reduce the alkyl chloride content of the mixture and this cannot be done by distillation because the alkyl chloride contaminants boil in the same range as the hydrocarbons.

The process of the present application involves a combination of steps which reduces substantially the amount of alkyl chloride contaminant in hydrocarbon mixtures, such as those obtained by the alkylation of isoparaffin with a low boiling olefin when using an active chloride as the catalyst. The process involves the steps of bringing a vaporized mixture consisting of hydrocarbons in the gasoline boiling range and contaminated by a small amount of alkyl chloride or chlorides into contact with bauxite and removing the mixture from contact with the bauxite, condensing it and subjecting the condensed liquid to hydrolysis. A hydrocarbon fraction is removed from the hydrolysis step which is substantially free from alkyl chlorides and is a desirable component for inclusion in gasolines.

By way of explanation of the satisfactory results obtained, we have discovered that the alkyl chloride in admixture with the hydrocarbons, which are obtained by the alkylation of isoparaffin with a low boiling olefin when using active chloride catalyst, is primary alkyl chloride. When such a contaminated hydrocarbon is vaporized and contacted with fresh bauxite, substantially all of the alkyl chloride is removed from the hydrocarbons by catalytic dehydrohalogenation, but as the bauxite ages in use, the effluent contains hydrocarbons contaminated by secondary and tertiary alkyl chlorides which are considerably more detrimental to the quality (leaded octane number) of gasoline than the primary alkyl chloride in the feed stock, but unlike the primary alkyl chloride may be readily removed from the hydrocarbons by hydrolysis. Thus, the method of the present invention involves the substantial removal of alkyl chloride

contaminants from hydrocarbons in the same boiling range by a two-step process which does not require the frequent regeneration of the bauxite which is used in the first step of said process.

5 In conducting our process the feed stock contaminated with the primary alkyl chloride or chlorides is vaporized and the vaporized mixture is contacted with bauxite. It is preferred to carry out the contacting step at a temperature within 10 the range of 500° to 900° F. with a contact time of .01 to 1 second. The bauxite may remain on stream for as long as 24 hours without regeneration and satisfactory results obtained. It may be noted that when the bauxite has been freshly 15 regenerated it apparently acts as a dehydrohalogenation catalyst, so that the effluent removed therefrom is substantially free from alkyl chloride for the first 6 to 8 hours the bauxite is in service and usually is given no further treatment.

20 Thus, generally, a bauxite bed which has been in service as a catalyst for from 8 to 24 hours after its last regeneration is the contacting material used in the first step of our process.

The hydrocarbon product removed from contact with the bauxite and which is contaminated with secondary and tertiary alkyl chlorides is hydrolyzed in the presence of an aqueous caustic solution. The hydrolysis step may be carried out at temperatures within the range of 180° to 500° 25 F. If the lower temperatures within the range given are used, it is necessary that a considerable time of contact be used. Hence, for commercial purposes it is usually desirable to hydrolyze under pressure at a temperature between 290° and 500° 30 F. for a contact time within the range of 3 to 50 minutes.

35 After the bauxite used in the first step of our process has been on stream a considerable length of time, the chloride content of the effluent becomes so great that it is desirable to regenerate it. The length of time the bauxite bed may remain on stream may be varied at the option of the operator. However, for commercial purposes it will usually be desirable to regenerate the 40 bauxite bed after it has been on stream 24 or 30 hours. As explained heretofore, the fresh bauxite removes substantially all of the alkyl chlorides from the gasoline by catalytic dehydrohalogenation so that usually the process of the present invention is not carried out with a freshly regenerated bed of bauxite. For practical purposes, a bauxite bed which has been on stream a minimum of 6 to 8 hours, and a maximum of 24 to 30 hours is used in the first step of our process. The 45 method for regenerating a bed of bauxite is well

2

known to the art. By way of example, the bauxite bed may be regenerated by passing steam through it at a temperature in the range of 500 to 900° F. for no less than 30 minutes.

The method for carrying out the present invention will be described in greater detail in conjunction with the drawing in which the figure is in the form of a flow sheet illustrating a mode for practicing the invention.

Turning now specifically to the drawing, feed stock consisting of hydrocarbons in the gasoline boiling range which is contaminated by a small amount of primary alkyl chloride or chlorides in the same boiling range is passed through inlet line 11 to vaporizer 12 where the mixture is vaporized and is withdrawn through line 13 and sent to chamber 14 containing a bed of bauxite 15. As heretofore explained the bauxite used is generally on stream for the time interval of 6 or 3 hours to 24 hours after its last regeneration. The effluent from chamber 14 is withdrawn through line 16 and passed through condenser 17 where it is liquefied and the liquid is withdrawn through line 18 and passed to hydrolyzer 19. Aqueous caustic solution is introduced to the hydrolyzer through inlet line 20 and spent aqueous solution is withdrawn through outlet 21. A desired product having a sufficiently low alkyl chloride content to make it suitable for inclusion in gasoline is withdrawn through outlet line 22.

The invention will be further described by the following example:

Example I

The C₇₊ bottoms resulting from the distillation of the alkylate product resulting from the alkylation of isobutane with ethylene was contaminated with primary chlorides reported upon analysis at 0.223 weight per cent Cl. This mixture was vaporized and contacted with a bed of bauxite at a reactor temperature of 700° F. at a pressure of 70 p. s. i. g. with a contact time of 0.1 second. The effluent was condensed. A sample withdrawn after the bauxite bed had been on stream for approximately 12 hours and which contained secondary and tertiary chlorides in an amount reported as 0.07 weight per cent chlorine was hydrolyzed. Because pressure equipment was not available for this hydrolysis step a relatively low temperature of 190° F. was used and the product was hydrolyzed for 18 hours with an aqueous caustic solution of 5 weight per cent strength. The improvement obtained in treating this sample is shown by the fact that the material charged to the bauxite treater, having 0.226 per cent chlorine had a leaded research octane number (Octane by Research Method; Test D-908; ASTM Manual of Engine Test Methods for Rating Fuels, March, 1948) of 91.6 and a leaded 3-C rating (Rich Mixture Rating; Test D-909; ASTM Manual of Engine Test Methods for Rating Fuels, March, 1948) of 77; the condensed effluent from the bauxite treater having a chlorine percentage of 0.07 had a leaded research octane number of 90.6 and a leaded 3-C rating of 69; while the hydrocarbons withdrawn from the hydrolysis step with 0.02 weight per cent chlorine present had a leaded research octane number of 91.9 and a leaded 3-C rating of 82.

In order to show the advantage of the method of the present invention involving the combination of bauxite treatment followed by hydrolysis, the unsatisfactory results obtained when using hydrolysis alone are shown in the following example:

Example II

A total ethylene alkylate, resulting from the alkylation of isobutane with ethylene employing aluminum chloride catalyst, was contaminated with primary chlorides, reported upon analysis as 0.0459 weight per cent chlorine. This mixture was hydrolyzed for 3 hours at 320° F. with an aqueous caustic solution of 5 weight per cent strength. It was found that the treated material still contained 0.0437 weight per cent of chlorine.

It is seen that under relatively severe hydrolysis conditions in Example II, the amount of original primary chlorides present in the alkylate could be reduced by only about 5% of the amount originally present. In Example I it was shown that the amount of secondary and tertiary chlorides present in the alkylate after passage over bauxite could be reduced by a relatively mild hydrolysis from 0.07 to 0.02 weight per cent or by about 71% of the amount present.

In explanation of the advantages resulting from the method of the present case, it is to be emphasized that when passing the mixture through the bauxite bed, the secondary and tertiary alkyl chlorides which are discharged with the hydrocarbons from the bed after the bed has been in use for several hours after its latest regeneration step are more detrimental to the octane number and particularly to the rich mixture rating, than are the primary alkyl chlorides originally present in the charge stock. Thus, in Example I the material withdrawn from the bauxite bed had approximately 1/3 the chlorine content of the original feed stock, yet its leaded research octane number was 90.6, and its leaded 3-C rating was 60, whereas the original feed stock had a leaded research octane number of 91.6 and a leaded 3-C rating of 77. It is for this reason that the effluent removed from contact with the bauxite bed is unsuitable for inclusion in motor gasoline, and particularly unsuitable for inclusion in aviation gasoline, if the bed has been on stream as much as about 6 to 8 hours after its previous regeneration. Even though the alkyl chloride content of the effluent is much lower than that of the charge stock, the alkyl chlorides are secondary or tertiary rather than primary and so are much more detrimental to the leaded octane number and 3-C rating of the product.

Having fully described and illustrated preferred methods for performing the present invention, what we desire to claim as new and useful and to secure by Letters Patent is:

1. A method for treating a mixture consisting of hydrocarbons in the gasoline boiling range contaminated with a small amount of primary alkyl chloride capable of being converted to secondary and tertiary alkyl chlorides and boiling in the same range as the hydrocarbons which includes the steps of vaporizing the mixture and contacting the vaporized mixture with bauxite at a temperature within the range of 500° to 900° F. at a pressure of 70 p. s. i. g. for a time from 0.01 to 1 second to convert substantially all of said primary alkyl chloride therein at least a portion of said primary alkyl chloride being converted to secondary and tertiary alkyl chlorides and removing as an effluent from contact with the bauxite the vaporized hydrocarbon contaminated with secondary and tertiary alkyl chlorides and substantially no primary alkyl chlorides, condensing the effluent and contacting the condensed effluent with aqueous caustic solution in a hydrolysis step at a temperature within the

range of about 180° to 500° F. for a time sufficient to hydrolyze substantially all of said secondary and tertiary alkyl chlorides, and then separately removing a hydrocarbon fraction substantially free of alkyl chlorides from said hydrolysis step.

2. A method in accordance with claim 1 in which the mixture treated is a C₇₊ fraction resulting from the distillation of product obtained by alkylating isoparaffins with a low boiling olefin in the presence of an aluminum halide catalyst.

3. A method for treating a hydrocarbon mixture containing C₇₊ hydrocarbons contaminated with a small amount of primary alkyl chloride capable of being converted to secondary and tertiary alkyl chlorides boiling in the same range as the hydrocarbons which includes the steps of vaporizing the mixture and contacting the mixture with a bed of bauxite at 700° F. at a pressure of 70 p. s. i. g. for 0.1 second to convert substantially all of said primary alkyl chloride contained therein, at least a portion of said primary alkyl chloride being converted to secondary and tertiary alkyl chlorides, and removing as an effluent from contact with the bed of bauxite vapor-
